Primary Examiner — Keith J Wilson

(57) **CLAIM**

The ornamental design for a device for blowing air as shown and described.

DESCRIPTION

1. Device for blowing air

1.1 : Perspective

1.2 : Right

1.3 : Left

1.4 : Bottom

1.5 : Top

1.6 : Back

1.7 : Front

The characteristic features of the design lie in the shape of the device for blowing air as shown.
